(57) **CLAIM**

We claim the ornamental design for a camper's/traveler's toilet paper protector with snap-on lid, as shown and described.

DESCRIPTION

FIG. 1 is a perspective view of a camper's/traveler's toilet paper protector with snap-on lid showing our new design in use; the broken lines depict environmental structure for illustrative purposes only and form no part of the claimed design;

FIG. 2 is a side elevational view thereof, all other side elevational views being identical thereto;

FIG. 3 is a top plan view thereof; and,

FIG. 4 bottom plan view thereof.

1 Claim, 3 Drawing Sheets

FIG. 2.

FIG. 3.

FIG. 4.
